STOKER

Charles C. Kirby, Decatur, Ill.

Application August 15, 1934, Serial No. 739,848

3 Claims. (Cl. 110—115)

This invention relates to a novel and improved stoker for coal furnaces and the like, and has for its principal object an automatically controlled and measured output of fuel which is fed into the fire bed of the furnace.

Another important object of the invention is the provision of a novel, simple and highly efficient means for distributing the fuel in an even and uniform layer over the entire fire box area, thus accomplishing more complete and efficient combustion of the fuel in the furnace.

A further important object of the invention is the provision of a stoker which is built into a complete portable unit, and which may be cheaply manufactured to perform its operations in a positive and effective manner.

A further important object of the invention is the provision in a stoker of mechanism for manually varying the amount of fuel delivered by the stoker into the furnace in an amount proportionate to the size of the fire box in the furnace.

A still further object of the invention is the provision of means for automatically restraining the delivery of fuel after a predetermined amount has been fed into the fire box, and for automatically releasing said means to start a new delivery of fuel.

Another object of the invention is the provision of means whereby the fuel delivered into the fire box of the furnace will be maintained below a predetermined size.

Numerous other objects and advantages of the invention will be apparent as it is better understood from the following description, which, taken in connection with the accompanying drawings, discloses a preferred embodiment thereof.

On the drawings,

Figure 1 is a side view of the stoker embodying my present invention connected to a furnace and showing the hopper, screw conveyer, and distribution chamber in section;

Fig. 2 is a horizontal section taken substantially on the line 2—2 of Fig. 1;

Fig. 3 is a fragmentary enlarged sectional view of a portion of the hopper and screw conveyer and shows the adjustable feed control mechanism;

Fig. 4 is a section taken substantially on the line 4—4 of Fig. 3;

Fig. 5 is a fragmentary view showing a portion of the feed control mechanism in a different position from that shown in Fig. 3;

Fig. 6 is a perspective view of the distribution chamber;

Fig. 7 is a perspective view of the distribution disk;

Fig. 8 is a perspective view showing the screw conveyer insert for preventing oversize lumps of fuel from entering the conveyer screw;

Fig. 9 is a plan view of a modified form of distribution disk; and

Fig. 10 is a wiring diagram of the circuit for automatically operating the stoker.

Referring to the drawings, the stoker is shown comprising a storage hopper 10 having at its upper end a lid or closure 11, front and side walls 12 sloping inwardly from top to bottom to form a trough-shaped portion 13 at its lowest extremity and a vertically disposed rear wall.

The trough portion 13 may be welded or otherwise secured by an angle band 14 to effect a sealed closure with a member 15 of tubular form having teeth 16 along the upper edge and along one of the vertical edges of an aperture 17, the teeth 16 serving to break up any unduly large lumps of fuel which may have entered the hopper.

The member 15 is adapted to embrace a vertically disposed screw conveyer tube 18, which is provided at its lower end with a notch or aperture 19 corresponding in height to the trough 13 and is cut back in depth to its axis as shown at 20, to allow for the entrance of the fuel. Adjacent and below the aperture 19 the tube 18 is rigidly mounted in any desired manner on the frame or housing of a gear reducer 21.

The conveyer tube 18 has at its uppermost end 30 a notch or aperture 22 to provide an exit for the fuel into a distribution chamber housing, generally designated by reference character 23.

A screw conveyer 25, fixed to a driven shaft 26, is adapted to rotate within the conveyer tube 18 and extends to practically the full length thereof, i. e. from the base of the trough 13 to the lower end of the upper aperture 22. Adjacent the lower portion of this screw 25 is a cup-shaped closure member 27 which is adapted to snugly 40 embrace the inner wall of the tube 18 and the shaft 26, thus preventing any escape of dust or foreign matter into the mechanism directly below, as will be later described.

The screw 25 has at its upper end a paddle-shaped member 28 in registration with the notch 22 and adapted to be fixedly held on the conveyer shaft 26 so that the screw and paddle will rotate in unison.

Referring now to Fig. 1, the gear reducer 21 is fastened rigidly by means 31 to a rectangular-shaped base or support member 32 having casters 33 which may either be fixedly or swivelly mounted, the base member also serving to support the storage hopper through supports 34.

Referring now to the main drive mechanism, I have provided a motor 35 vertically disposed and spaced apart from the conveyer tube 18 having bearing at its lower end at 36 on the frame of the gear reducer 21 and having a motor drive shaft 37, the lower extension of which constitutes a drive through the reducer gears 38 to the screw conveyer shaft 26.

The housing 23 comprises a semi-circular portion 40 extending vertically and conforming to and embracing the outer and upper portion of the conveyer tube 18, a pair of outwardly flaring side portions 41 and a horizontal base portion 42 which is formed with a flange portion 43 to enclose the tube 18. The distribution chamber terminates in an opening 44 which is adapted to abut a door 45 of a furnace 46, this door having an opening 47 of width and length to match the opening 44. To preclude leakage of dust, etc., during the operation of the stoker, an angle iron strip or other suitable means 47' is or may be welded around the periphery of the opening 44 to abut against the door 45.

It will be noted that the outwardly flaring sides 41 of the distribution chamber (Fig. 1) have a top horizontal edge 48, and downwardly sloping edges 49, continuing into a horizontal edge 50 which terminates at the furnace door 45. A cover plate 51, whose surface conforms to and rests upon the edges of the distribution chamber, serves as an enclosure for this chamber. A removable plate 52, held in place by means 53 above the opening 44, is provided for the purpose of observing the condition of the fire box from time to time as desired.

Referring now to the portion of the conveyer tube immediately below the aperture 22, an inclined guide chute 55 is formed and fastened to the tube at 56. The chute extends downwardly to within a normal working distance of the distributor disk 39 and in its extension may preferably be arcuate in form. A deflector bar 58 is pivoted at 59 to the lower end of the guide chute 55.

The distributor disk 39 comprises a rotating circular disk 61 having a plurality of blades 62 fastened to its upper surface by bolts 63, or other suitable fastening means. The blades 62 may be of angle iron form and, as will be seen from Figs. 2, 7, and 9, are placed with their outermost ends 64 diametrically opposite one another and in close proximity to the periphery of the rotating disk. These blades extend along the surface of the disk with their vertical planes lying on either side of its axis and equidistant therefrom. The blades are parallel to one another and terminate at 65 just before reaching the center of the disk. Slots 66 are or may be provided for angular adjustment of the blades if desired (see Fig. 9).

The distributor disk is rigidly secured to the upper extension of the motor drive shaft 37 by suitable means 67. Referring to Fig. 1 it will be apparent that the distributor disk assembly is positioned in close proximity to the base of the distribution chamber housing 23, which obviates the danger of pieces of fuel or foreign matter lodging beneath the distributor disk. A housing 68 is provided for protection from the rotating motor shaft 37 and may be suitably fastened at 69 to stationary hubs 71.

Before describing the coal output controlling means, a brief explanation of the operation of the parts thus far described may serve to more clearly disclose the invention. Assuming that the

circuit for the motor is closed, rotation of the motor shaft which normally runs at 1750 R. P. M. will, through the gear reducer, rotate the conveyer screw at a speed of about 20 R. P. M. The relationship of these speeds will become apparent as the invention is later described. Fuel will be fed up the screw and to the paddle-like structure which tends to prevent any crowding of the fuel, the fuel then dropping by its own weight down the inclined chute and onto the rotating distributor disk. The staggered blades on the disk tend to hurl the pieces of fuel through the opening in the fuel door of the furnace and into the fire box chamber. This operation continues until automatically stopped.

The mechanism for accomplishing this automatic stopping (Figs. 3 to 5) comprises a ratchet wheel 75, pinned at 76 to a horizontally disposed shaft 77 having bearing at 78 in a support or bracket 79 which in turn is rigidly secured at 80 to the gear reducer housing 21.

Fastened to the support 79 at 81 and vertically disposed relative thereto is a second support 82 having a horizontal bearing 83 adapted to receive an adjustable tubular sleeve 84, the inner or rearward end of which extends through an opening in the conveyer tube below the cup-shaped closure member 21. The outer or forward end of the sleeve 84 has an enlarged or spring housing 85 secured thereto and adapted to house a coiled spring 86 which normally urges a reciprocating rod 87 inwardly or rearwardly against a shoulder 88 in a reduced portion of the bore of the tubular sleeve, the spring 86 abutting against the head of the housing 85 at its forward end and being secured at its rearward end to the rod 87 in any desired manner.

The reciprocating rod 87 has a correspondingly reduced portion 89 which extends from the shoulder 88 beyond the end of the tubular sleeve to abut against an eccentric 91 which may be pinned or otherwise fastened to the screw conveyer shaft at 92. This rod extends beyond the spring housing member 85 and is provided with a flattened portion having a pivot 93 for a connector link 94 in turn loosely pivoted at 95 to a lever or arm 96. The lever or arm is loosely mounted on the shaft 77 and is provided with a ratchet dog or pawl 97 adapted to drive the ratchet wheel in a counter clockwise direction, viewing Figs. 3 and 5.

Also mounted on the ratchet wheel shaft 77 opposite the ratchet wheel and adjacent the bracket 79 is an arm 98 rigidly fixed to the shaft 77 at 99 and pivoted at 100 to a connecting link 101. The link 101 is pivoted to an arm 102, fixed to a stub shaft 103 adapted to operate a switch 104, to be described hereafter, within a housing 104.

Referring to the support 82, it will be noted that an extension 105 is provided, extending above and forming a part of the horizontal bearing 83 in the support. This extension 105 is provided with an opening 106 adapted to receive a plunger 107 having a knurled head 108 at its upper end and a conical-shaped member 109 at its inner end. The conical member 109 is normally urged into any one of a series of corresponding conical openings 110 by a spring 111 within an enlargement of the opening 106. The openings 110 are located in the upper surface of the adjustable tubular sleeve 84, and a key and keyway (not shown) prevents the tubular sleeve from rotation about its axis and consequent misalignment of the openings 110 with the plunger. 75

The operation of this mechanism is such that at each complete revolution of the conveyer screw shaft the eccentric cam urges the reciprocating rod 87 against the pressure of the spring 86 and 5 away from the shoulder 88 in the sleeve 84.

Motion is thus imparted to the arm 96 which, through its pawl 97, rotates the ratchet wheel 75 through a portion of its circumference, after which the spring 86 urges the mechanism to its 10 original position as shown in Fig. 3. The motion of the ratchet wheel, which is fixed to the shaft, imparts a corresponding degree of motion to the linkage and to the switch. A complete revolution of the ratchet wheel serves to oscillate the switch 15 operating shaft from an open to a closed position and back to open position. To prevent any but a uni-directional motion of the ratchet wheel a gravity held latching dog 117 is provided, which is pivoted at 113 in the ratchet shaft support 79. 20 It will be apparent that the longest possible stroke of the rod 87 and pawl 97, which would correspond to the complete throw of the eccentric 91, will impart a complete revolution to the ratchet wheel 75 in the shortest possible time, and this 25 may be interpreted as the minimum time for delivery of the fuel to the furnace.

In order to selectively vary the fuel delivery, and consequently the timing, the spring held plunger 107 is drawn by the knurled head 108 30 out of its associated conical opening 110 and the tubular sleeve 84 is adjusted to accomplish registration of the plunger with an adjacent opening, it being understood that any number of 35 adjustments may be incorporated without changing any of the desirable features.

The mechanism just described is illustrated in Fig. 5 and it will be apparent that in the new adjustment therein shown the entire ratchet driving assembly will be drawn forwardly or outwardly 40 leaving a gap between the end of the reduced portion 89 and the engaging surface of the eccentric 91. In this manner the distance travelled by the ratchet wheel for each revolution of the eccentric will be lessened, necessitating a larger 45 number of revolutions for the screw conveyer shaft to complete one revolution of the ratchet wheel, which constitutes a complete cycle of operation. Moving the plunger into still another notch will again vary the time of a complete 50 cycle.

It will be apparent that this mechanism may be operated effectively by an unskilled operator and that it provides for a series of adjustments for varying fuel capacities for different sizes of 55 furnaces.

Referring now to the distributor disk and its associated parts, it will be remembered that this disk rotates at a relatively high speed while the fuel conveyer screw rotates at a relatively low 60 speed, for example in the ratios of 1750 R. P. M. to 20 R. P. M. respectively. The coal is brought into the distribution chamber where it falls normally by its own weight onto the rapidly whirling distributor disk, the blades on the distributor disk 65 carry the fuel with it and the centrifugal forces tend to throw the fuel away from the whirling disk and into the furnace. As the fuel leaves the guide chute it will contact or strike the blades at different points along their presented faces thus 70 varying their angular directions on leaving the disk. The fuel is thus directed into the furnace in a plurality of varying angular directions until every portion of the area of the fire box is covered with a uniform and evenly distributed layer.

75 Spreading a layer of fuel on a fire bed in this

manner causes a more even and intense distribution of heat within the combustion chamber and enables steam to be generated in a much shorter time than is required in the methods now employed where the fuel is either heaped or 5 banked in the fuel box.

Exhaustive tests have shown that preparing the firebox in the manner hereinbefore described has resulted in greater efficiency in the operation of the furnace with a much finer ash deposit and 10 less clinkers than has heretofore been possible. It has also been found that placing the motor in the position illustrated on the drawings has served to keep it cool, a factor which is most important in the upkeep of the machine. 15

The invention is also intended for automatic operation and to this end Fig. 10 discloses a wiring diagram in which leads 117 and 118 may be connected to any electric outlet to operate the motor 35. A switch 121, connected in parallel 20 with other switches in the circuit, is the switch referred to above as being within the housing 104 and oscillated by the linkage of the ratchet wheel mechanism previously described and closes the circuit through contact with the segment 122. 25 When the ratchet wheel mechanism has completed its cycle of operation the switch is thrown into an open circuit position, as shown in broken lines in this figure. A thermostatic switch 123, connected in series with the motor 35 and in 30 parallel with the switch 121, may be used to close the circuit to the motor when the temperature at any desired control point in the heating system falls below a predetermined point. When this takes place the stoker will operate through 35 another complete cycle and be stopped, unless the thermostatic switch is still closed, which will automatically initiate another complete cycle of operation. These two switches will automatically control the operation of the stoker without any attention except for the replenishing of 40 fuel to the hopper.

A third and manually operated switch 125 may be employed to initially start the device into 45 operation, and this switch is held in a normally inoperative position by a spring 126. This switch 125 may be mounted on or within the housing 104 for convenience, if desired, as shown in Fig. 3. In its initial operation, the switch 125 is urged into a closed circuit position, the operator holding the switch in this position momentarily until the switch 121 acts to close the circuit to the motor, after which the switch 125 is released. It is apparent that a full automatic switching arrangement might be provided, the form shown 50 on the drawings being merely a preferred arrangement and forms no part of the present invention.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof. 60

I claim:

1. In a furnace stoking mechanism, a charging chamber having a discharge outlet adapted 70 to communicate with a furnace, a horizontal rotary impeller in the lower portion of said chamber, a hopper, extending to a point below the charging chamber, a screw conveyor arranged to convey fuel upward from said hopper to said 75

charging chamber, means in the charging chamber directing the fuel to the impeller, a motor below said impeller, a shaft substantially parallel to said conveyor extending vertically from said motor and operatively engaging said impeller and motor, and means operatively connecting said motor and said conveyor.

5 2. In a furnace stoking mechanism, a charging chamber having a discharge outlet adapted to communicate with a furnace, a rotary impeller in the lower portion of said chamber, a hopper extending to a point below the charging chamber, a screw conveyor arranged to convey fuel upward from said hopper to said charging chamber, means in the charging chamber directing the fuel to the impeller, a motor below said impeller, a shaft substantially parallel to said conveyor extending upward from said motor and operatively engaging said impeller and said conveyor.

motor, and means operatively connecting said motor and said conveyor, said means being so constructed and arranged as to fix the relative speeds of said conveyor and said impeller at a predetermined ratio.

3. In a furnace stoking mechanism a charging chamber having a discharge outlet adapted to communicate with a furnace, a rotary impeller in said chamber, a hopper extending to a point below the charging chamber, a screw conveyor arranged to convey fuel upward from said hopper to said charging chamber, means in the charging chamber directing the fuel to the impeller, a motor below said impeller, a shaft substantially parallel to said screw conveyor extending upward from said motor and operatively engaging said impeller and motor, and means operatively connecting said motor and said conveyor.

CHARLES C. KIRBY.
